UNITED STATES PATENT OFFICE.

ADNA F. BLANCHARD, OF CRANSTON, RHODE ISLAND, ASSIGNOR, BY MESNE ASSIGNMENTS, TO FAIRFIELD MANUFACTURING COMPANY, OF CRANSTON, RHODE ISLAND, A CORPORATION.

COMBINATION POCKETKNIFE AND NAIL CLIP.

1,424,551.

Specification of Letters Patent. Patented Aug. 1, 1922.

Continuation in part of application Serial No. 322,981, filed September 10, 1919. This application filed April 2, 1920, Serial No. 370,753. Renewed November 30, 1921. Serial No. 519,030.

To all whom it may concern:

Be it known that I, ADNA F. BLANCHARD, a citizen of the United States, residing at Cranston, in the county of Providence and State of Rhode Island, have invented certain new and useful Improvements in Combination Pocketknives and Nail Clips, of which the following is a specification.

This application is a continuation in part 10 of my co-pending application filed September 10, 1919, Serial Number 322,981.

The invention has for an object to provide a combination pocket knife and nail clip, in which there are utilized well known 15 elements of pocket knives in such a manner that the cheek plates or handle portions may be utilized as clip devices for clipping finger nails and the like. It is a further important aim of the invention to 20 effect improvements in such a device whereby by the clipping action will be made quite easy by the provision of means which will increase the leverage of the arm by which the clip portion is operated, and whereby 25 in the closing of the device, when not in use, excessive pressure upon the clipping blades is obviated as well as ease in closing the device attained.

Additional objects, advantages and features of invention will appear from the construction, arrangement and combination of parts hereinafter described and shown in the drawings presenting one embodiment 30 of the invention, wherein,

Figure 1 is a perspective view of an implement constructed in accordance with my invention, in open position,

Fig. 2 is a side elevation thereof, closed,

Fig. 3 is an enlarged longitudinal sectional view of the operative parts at the clip end,

Fig. 4 is a plan view of the blank for one cheek plate,

Fig. 5 is a similar view of the blank for the opposite cheek plate,

Fig. 6 is a plan of the blank for the operating lever,

Fig. 7 is a detail enlarged side elevation of the fulcrum end of the lever,

Fig. 8 is an enlarged perspective view of the fulcrum member detached,

Fig. 9 is a plan view of the blank for the fulcrum member.

There is illustrated a combination knife and nail clip, comprising two handle plates 55 10 and 11 respectively, which are secured directly upon knife springs 12 and 13 and an interposed lining plate 14 between the springs, there being no lining plate at the outer sides of the device beneath the plates 60 10 and 11, in the present instance. Blades 15 and 16 are pivoted in a usual manner at one end of the device between the plates 10 and 11; the blade 16 is a nail file and cleaner.

It should be noted that the springs 12 and 13 are not secured between the plates 10 and 11 at the end opposite the pivot in the blade in the usual manner familiar in the art, and the plates 10 and 11, which correspond to 70 the ordinary lining plates, are projected slightly beyond the springs and middle lining plate at that end of the device opposite the pivot of the blades. The springs and plates are secured together by an intermediate rivet 17 having the usual location with respect to the pivot 18 of the blades, but the extremities of the springs opposite the pivot are not secured to the outer plates at all, although they may be secured together 80 upon the lining plate 14 as indicated at 19.

In the present case, the second point of securing of the spring to an outer member is at 20, a point intermediately of the rivet 17 and the ends of the springs opposite the 85 blade pivot. This securing may be of an ordinary character, which would leave the plates 10 and 11 free for relative flexure from this point outwardly on their adjacent extremities. But, in the present instance, I 90 have shown the springs as riveted to the plate 10 only as at 20, but the rivet is formed with a taper tenon 21 inserted loosely in a recess or aperture in the plate 11. By this construction, the plate 11 is 95 permitted relative movement from its point of securing at 17, and the plate 11 is supported against the ordinary stresses to which it would be subjected as a part of a knife handle by the pivot 18 and the tenon 100 21, in addition to the rivet 17.

The extensions of the handle plates 10 and 11 are provided with nail clip jaws or blades 22, a short distance outwardly of the springs, and reinforcing flanges 23 are 105 formed on each side of these extensions pro-

jected inwardly and extending throughout the length of the extensions. The extensions of the plates 10 and 11 to form the clips may be termed clip jaws 10' and 11', respectively. It should be noted that the plates are given a set causing these jaws to tend to incline outwardly from each other toward their outer ends, and that the plate 11 may diverge from the knife springs beginning at the rivet 17 and extending over a major part of the length of the knife handle.

In the jaw 11' there is set a stud 24, having a tenon 25 projected through an aperture 26 of rectangular form extending longitudinally of the jaw countersunk on the outer side. The tenon 25 is peened in this aperture, so as to form a dove-tail connection. The stud is stamped from sheet metal, and the tenon 25 may be formed by notching the base of the stud at opposite corners, the intermediate portion of this tenon being the full thickness of the blank and adapted to fit snugly between the sides of the aperture 26 when inserted. The stud is provided at its outer end with a transverse pin 27, the axis of which is in the present instance between the jaws when in open position as shown in Fig. 7. Pivoted upon this pin there is a lever 28 formed from a blank of sheet metal bent into U-shape in cross section, provided with ears 29 at each side, mounted upon the pin 27, these ears being projected laterally from the lever in parallel relation and being engaged through an aperture 30 formed in the plate 10 having proper dimensions to receive the parts loosely, for the function to be described. The inner longitudinal edges of the lever are so extended as to lie flat upon the plate 10 and within a recessed portion 31 thereof when the two plates have been moved inwardly toward each other until the blades 22 nearly or quite engage, and a sliding latch 32 is provided to engage over the end of the lever when in this position to hold the parts in closed relation. By having the tenon 21 slightly tapered, when the parts are forced inwardly into this position, the plate 11 will fit tightly upon the tenon so that when the device is used for cutting with the blade, liability of loose movement of the plate 11 will be obviated. It is believed, however, that the pivot 18 and rivet 17 are sufficient in themselves for this purpose.

The device might be utilized in this form as a nail clip, but in order to provide for proper clipping coaction between the blades 22, and also to give a shiftable fulcrum for the device whereby the fulcrum will be as near as possible to the pivot of the lever, or otherwise located for the most efficient application of force through the lever, I have provided in the lever a longitudinally shiftable fulcrum 31. This fulcrum consists of

a transverse bar from which there is extended at right angles a stem 32 laid within the lever close to the bight portion, as viewed in cross section, and having a lateral T-shaped extension 33 at one side, the head portion of which is inserted through a slot 34 formed medially in the lever, the head portion extending transversely of the slot so as to hold the fulcrum device in place. The retaining portion 33 is put in position by first twisting the stem 32 adjacent the bar 31 for a quarter turn, and after inserting the member 33 through the slot 34, the head portion is given a quarter turn twist also, to set it transversely of the slot. For the functioning of the fulcrum, the lever is provided with two notches next to the jaw 10' on each edge close to the ears 29. The outer notch 35 is a shallow one, while the notch further from the ears is a deep one 36 and is adapted to receive the ends of the fulcrum bar 31 loosely when the parts are in closed position as shown in Fig. 3, or the notch may be so shaped that the fulcrum will be borne against the jaw 10' so as to hold the parts in the position shown in Fig. 3, or such other position as may be determined upon as desirable in the closed position of the parts. In the present instance, the drawing indicates that there is still a clearance between the slip portions of the plates 10 and 11, and the adjacent end portions of the knife springs, even when the device is in closed position. This would permit a further convergent movement, for clipping of nails, and compensate for wear in use, sharpening, or otherwise.

In order to use the device for a nail clip, presuming the device in closed position, the latch member is moved upon the handle to clear the lever which is then thrown outwardly by opening action of the jaws. The fulcrum bar will at this time be in the notches 36, and the shifting head 33 on the stem of the lever will be at the inner end of the slot 34, with respect to the knife handle. The head 33 is adjusted with sufficient loose movement to permit the fulcrum member 31 to fall below the notches 36 when the lever is raised, or the stem 32 may be made resilient so that when pressure is exerted upon the head 33 to cause it to slide outwardly upon the lever the fulcrum member will be moved from the notches 36 into the notches 35. In order for the fulcrum to engage under the notches 35 it is necessary to raise the lever to a considerable height. Upon downward pressure of the lever then, the jaws are readily compressed into contact, and it is easy to apply sufficient pressure to clip a nail.

The plates 10 and 11 may be pressed into form with their intermediate parts pressed outwardly, so as to give a good rounded handle, therein in case they are stamped

from sheet metal, and the channel 31 may be cut or pressed in the plate 10, as found most desirable.

What is claimed:

- 5 1. A combined pocket knife handle and nail clip comprising a handle body including resilient lining plates, a knife spring secured to the plates a distance from the pivot and secured to one plate a greater distance 10 from the pivot short of the end of the spring body, said plates tending to diverge beginning intermediately of the handle, said plates being projected beyond the spring a distance and formed as clip devices, and 15 means to compress the clip devices.
2. In a combined knife and clip a handle body including resilient longitudinally extending plates and interposed knife springs, said plates projected beyond the handle 20 body at one end and formed thereat as clips, means to compress the clip portions, a connection between said plates intermediately of the handle one plate being fixed to the knife spring at a lesser distance from the 25 clips and a pin snugly slidable in the other there adjacent whereby it may flex and will be sustained as a handle element.
3. In a device of the character described, relatively movable clip jaws, a lever to operate the jaws having a release position and a 30 longitudinally shiftable fulcrum member thereon, said lever being notched and said fulcrum being movable to engage in said notch for inoperative relation of the parts.
- 35 4. In a clip device a pair of relatively movable clip jaws, one having a stud mounted thereon, the other apertured adjacent the

stud, a lever in the aperture pivoted on the stud and adapted to bear on said apertured jaw for compression of the clip and having 40 means to secure the lever in position closing the parts, the lever having notches, one of a size to receive the fulcrum member snugly when the parts are in closed position and another in a position to afford greater leverage and to engage the fulcrum for the purposes described.

5. In a clip device, a lever of sheet metal bent into U-shape in cross section and having a longitudinally slidable stem mounted 50 therein having a transverse fulcrum member at one end and notch portions in the lever to engage the fulcrum at different positions, the lever being connected to one element of the clip and said fulcrum having bearing on 55 the other member of the clip.

6. In a combination knife and clip, a knife handle body including two blade-mounting plates of resilient metal suitable for a cutting tool, said plates being extended 60 beyond the handle body at one end and shaped to form clip jaws relatively movable toward and away from each other, and having a set tending to spring them apart, and means to compress the jaws for clipping action including a lever extending inwardly beside the handle body.

In testimony whereof I have affixed my signature in presence of two witnesses.

ADNA F. BLANCHARD.
